UNITED STATES PATENT OFFICE.

EDWIN S. DECKER, OF MALDEN, MASSACHUSETTS, ASSIGNOR TO STEEL CABLE ENGINEERING COMPANY, OF BOSTON, MASSACHUSETTS, A CORPORATION OF MAINE.

COAL-BREAKER.

SPECIFICATION forming part of Letters Patent No. 758,302, dated April 26, 1904.

Application filed March 10, 1902. Serial No. 97,459. (No model.)

To all whom it may concern:

Be it known that I, EDWIN S. DECKER, a subject of the King of Great Britain, and a resident of Malden, county of Middlesex, State of Massachusetts, have invented an Improvement 5 in Coal-Breakers, of which the following description, in connection with the accompanying drawings, is a specification, like characters on the drawings representing like parts.

10 This invention relates to coal-breakers, and has for its object to provide a novel form of mechanism for breaking or disintegrating coal.

15 The mechanism now commonly employed for breaking up or disintegrating bituminous coal comprises one or more pairs of rollers between which the pieces of coal to be disintegrated are passed. This mechanism, however, has been found to have some disadvantages, and it is for the purpose of curing 20 these and for providing a coal-breaker that is capable of an increased output that I have made my present invention.

25 My novel coal-breaker comprises a barrel or mortar portion which is open at each end and in which is supported a rotary breaker. The breaker and mortar or barrel are so constructed as to form an annular space between them which is largest at the receiving end of 30 the barrel and diminishes in cross-sectional area toward the discharge end thereof.

35 One of the important features of my present invention resides in providing mechanism whereby the degree of fineness to which the coal may be broken or disintegrated may be readily regulated without the necessity of removing the breaker from the mortar or barrel and substituting a new one therefor of a different size. For this purpose one of the 40 parts, preferably the mortar or barrel, is constructed to removably support at its lower portion and in opposition to the lower end of the breaker an interchangeable series of disintegrating-teeth, the construction being such 45 that different-sized teeth may be employed, according to the degree of fineness to which it is desired to crush or break the coal or other material.

I have also provided my barrel with a removable lining, whereby as the lining becomes 50 worn it may be readily removed and replaced by a new lining, thus increasing the length of life of the device.

Other novel features of my invention will be hereinafter described, and pointed out in the 55 claims.

Figure 1 is a view of the apparatus, partly in plan and partly in section, the section being taken on the line *xx*, Fig. 2. Fig. 2 is an elevation of the apparatus, a portion thereof being shown in section. Fig. 3 is a section on line *z*, Fig. 2. Fig. 4 is a section on line *yy*, Fig. 5. Fig. 5 is a section through one side of the mortar. Fig. 6 shows different views of one of the wear-plates. Fig. 7 65 shows the closure-plate. Fig. 8 shows my preferred way of connecting the driving-pulley to its shaft, and Fig. 9 shows two teeth from different sets.

The mortar or barrel of the coal-breaker is 70 designated generally by 3, and, as illustrated, it is open at both ends thereof, the upper end being the receiving end into which the coal or other material to be disintegrated is deposited, the lower end thereof being the discharging end. For convenience I have constructed the barrel 3 with the base portion 4, adapted to be supported in any suitable way and having its central part open and bridged over by a suitable spider 6, and the hopper portion 5, which is detachably secured to the base portion and which, as illustrated, has flaring walls. The upper portion of the hopper carries a spider 8, in which is journaled in any suitable way one end of a shaft 7, carrying the breaker, presently to be described, the other or lower end of said shaft being mounted in suitable bearings in the spider 6. The base portion 4 has a plurality—four in this embodiment of my invention—of vertically-extending wings or holding-flanges 10, the upper ends of which are received in suitable grooves on the exterior of the hopper portion 5, said grooves being conveniently formed by means of two parallel ribs 11, cast 95 integral with the said hopper portion 5. The

base and hopper portions of the mortar also have registering ears 12 projecting therefrom which are bolted together, the said ears and the wings 10 serving to detachably secure the 5 two parts of the mortar together. I will preferably construct the hopper portion 5 of the barrel in three sections *a*, *b*, and *c*, respectively, the said sections being secured together by means of bolts passed through ribs 10 44 thereon. I prefer to thus make my hopper portion 5 in sections and to make the hopper portions separate from the base portion 4 in order to facilitate the shipment of the completed device.

15 The breaker that I preferably employ comprises a series of differently-shaped nuts or disks 19, (see Fig. 1,) which are fitted upon the polygonal-shaped portion 20 of the shaft 7 and which, therefore, must of necessity rotate with the shaft, the said nuts being of different sizes and of progressively-increased diameter from the upper nut or disk to the lower one, 19^a. These breaking nuts or disks have their periphery serrated in different 25 ways to form teeth of different sizes and shapes, which teeth during the rotation of the breaker operate, in conjunction with the inner face of the barrel, to break up and disintegrate the material, as will be obvious. The weight 30 of the shaft 7 and the breaker thereon is carried by a step-bearing 14, the said shaft being provided with a collar 14^a for resting upon the said bearing and antifriction-rolls preferably being employed to reduce friction. Fast to the shaft 35 at its lower end and between the breaker and the spider 6 is a bevel gear-wheel 15, which meshes with a gear 16, carried by a driving-shaft 17, which shaft in turn is journaled in any suitable way in the base portion of the 40 mortar and carries a driving-pulley 18, by means of which it may be rotated. These breakers are sometimes used in places where it is very desirable that the upper end or mouth of the hopper be comparatively unobstructed, and when such is the case I will locate the driving-gear for the breaker beneath 45 the same, as shown in the drawings. My invention, however, would not be departed from if the driving mechanism were at the upper 50 end of the shaft 7 instead of at the lower end thereof, and for some kinds of work this construction may be preferable. The inner face of the hopper portion 5 of the barrel is provided with a series of knobs or journals which 55 coöperate with the breaker in the disintegration of the material, and the final disintegration is accomplished by means of the lower disk or breaker-nut 19^a and a series of disintegrating-teeth 50, projecting from the operative face of the hopper.

60 It will be obvious that the degree of fineness to which the coal or other material will be disintegrated depends upon the distance between the periphery of the breaking-nut 19^a and the disintegrating-teeth 50, and it is one

of the important features of my present invention to provide means whereby this distance may be regulated or changed, as desired. The required regulation or variation in this distance may be accomplished by changing 70 the breaking-nuts for nuts of larger or smaller sizes; but as this entails considerable labor I will preferably accomplish this regulation by providing means whereby the disintegrating-teeth may be removably carried by the mortar 75 and by providing mechanism whereby any set of teeth may be easily and quickly removed and their place taken by a set of longer or shorter teeth, according as to whether it is desired to disintegrate the material to a greater 80 or less extent. To thus removably support the disintegrating-teeth 50, I have provided the hopper portion 5 with the annular groove 52 of the shape shown in Fig. 5, and in which groove the teeth 50 are supported, each tooth 85 having its outer end provided with a lip or projection 51 to fit the shape of the groove. This lip or projection 51 serves to lock the tooth into the groove, and in order to insert the teeth in the first instance I will preferably 90 provide an opening or keyway 53 through the side of the hopper of a size sufficient to receive the teeth 50 and through which the individual teeth will be inserted until the lip portion 51 comes into register with the 95 groove 52, when the said teeth will be moved sidewise into the groove. After all of the teeth have been thus inserted into the groove a key-tooth 55, Fig. 1, which is longer than the other teeth, will be inserted through the keyway, the end of the longer key-tooth partially 100 projecting into the keyway and being held in place by a cap-plate 56, which is secured to the hopper in any suitable way, as by screws 57. The object in making the key-tooth longer 105 than the other teeth is to lock the teeth against sidewise movement in the groove during the operation of the breaker, for it will be apparent to those skilled in the art that as the breaker is rotated the tendency will be to 110 give to the teeth 51 a movement around the barrel in the same direction as the rotation of the breaker. It will now be apparent that if for any reason it is desired to disintegrate the material to a greater or less degree the 115 disintegrating-teeth 50 may be readily removed by removing the key-tooth 55 and their place taken by longer or shorter teeth, according as to whether the annular space between the ends of the teeth and the breaking-nut 120 19^a is to be reduced or increased in width. Fig. 9 shows the relative length of the teeth of two different sets. It will be understood that any number of sets of different lengths 125 may be provided for use at different times in a single breaker. I will preferably construct a key-opening 53 in each one of the sections *a*, *b*, and *c* of the hopper 5 and will therefore have three key-teeth 55, this construction being preferable because it facilitates the inser- 130

tion or removal of the teeth when it is desired to substitute for them longer or shorter teeth.

It will be observed that the breaker and the barrel are held against relative movement in an axial direction and that provision is made for varying the size of the discharge-opening, and consequently the degree of fineness to which the material is broken or disintegrated, by providing an interchangeable series or set of disintegrating-teeth 50, the interchangeability of the series permitting longer or shorter teeth to be employed, as desired.

Another feature of my invention resides in providing a removable lining for the barrel, whereby as the lining becomes worn its place may be taken by a new lining. One convenient way of constructing the removable lining and of detachably securing the same in place is illustrated in the drawings. The hopper portion 5 is provided with an annular wear-plate-receiving recess 22, in which are adapted to be placed a plurality of wear-plates of the construction shown in Fig. 6. I have herein illustrated each wear-plate as having a curved inner face 23, from which project one or more projections 24, and a straight or plain back face 25. Referring to Fig. 3, it will be seen that the bottom of the recess 22 is made up of a number of straight sides 26, thus forming, in effect, a polygon, each side 26 being of the same size as the back face 25 of the corresponding wear-plate. The side edges 28 of each wear-plate are preferably substantially radial to the curved inner face 23, and by reason of this construction it will be apparent from Fig. 3 that after the series of wear-plates are inserted into the recess 22 they form a sort of arch construction, and each wear-plate is locked or held in position by the adjacent wear-plates. The object in making the back of the wear-plates with a plane surface so as to form a wear-plate-receiving recess having a polygonal shape is to lock the wear-plates against sliding around in the recess in the direction of rotation of the breaker, as they would tend to do if the recess were circular. In order to insert or remove the wear-plates, I have provided the upper flaring portion 30 of the hopper with an introduction-passage 31, opening into said recess, said passage being of a width sufficient to receive one of the wear-plates, and in practice this introduction-passage will be positioned directly over the place in which the last wear-plate is to be inserted. In order to insert the wear-plates, therefore, it is simply necessary to place the individual wear-plates in their position until all of the wear-plates have been inserted into the recess 22 with the exception of the wear-plate directly beneath the introduction-passage 31, when the last wear-plate may be inserted vertically into its place through the said introduction-passage. The arch construction of wear-plates serves to prevent any individual wear-plate

from becoming dislodged, and in order to hold the last wear-plate in position a closure-plate 40 (shown in Fig. 7) is inserted in the introduction-passage 31 and secured to the hopper in any suitable way, as by means of bolts. 70 For convenience I will preferably provide each section *a*, *b*, and *c* of the hopper with an introduction-passage 31 and a closure-plate 40, so that if it is desired to remove any wear-plate in any one section it is simply necessary 75 to first remove the closure-plate 40 from said section and then the wear-plate immediately under said closure-plate, when the other wear-plates of the section may be easily taken out.

After receiving its final disintegration between the disk 19^a and the teeth 50 the material drops through the open bottom of the barrel, as will be obvious, and in order to prevent it from dropping onto the shaft 17 or onto the gears 15 and 16 to clog the same a 85 shield or cover 60 is employed which rests on the wall or vertical flange 61, rising from the arms of the spider 6, said flange surrounding the gear 15 and having parallel substantially radial portions 62, which inclose the shaft 17, 90 as seen in Fig. 1. The shield or cover 60 is substantially circular, but has an extension 63 of a shape to rest on the parallel portions 62 of the flange 61 and to cover the shaft 17, the central portion of the cover having an aperture to receive a hub 65 on the lower disk 19^a. It will thus be seen that both the shaft 17 and the gears 15 and 16 are fully protected, and it will therefore be impossible for any of the coal to get onto and clog the teeth of the gears. 100 I would remark that the material after being pulverized drops through the skeleton bottom or base portion 4 outside of the vertical flange or wall 61.

It sometimes happens that a lump of some 105 hard substance gets dropped into the breaker, and to prevent the breaking-nuts or disintegrating-teeth from being damaged by such an occurrence I have provided a connection between the driving-pulley and the shaft 17 of such a construction that when the breaker meets with undue resistance the connection will break before any damage can be done to either the breaker or the disintegrating-teeth. One simple form of such connection is illustrated in Fig. 8, from which it will be seen that the web 81 of the driving-pulley is bolted or pinned to a flange 82 on a collar fast to the shaft. The material of which the pins or bolts 84 are made is such that they will be sheared or stripped by the web of the pulley when the breaker is subjected to undue resistance, though under ordinary circumstances they will be sufficient to drive the breaker. 115

From the above it will be seen that my invention comprises, broadly, a coal-breaker in which the degree of fineness to which the coal is broken is determined by providing an interchangeable set of disintegrating-teeth, whereby longer or shorter teeth may be em- 125 130

ployed, as required. It will therefore be obvious that the details of the construction may be varied in many ways without departing from the invention as expressed in the appended claims.

Having fully described my invention, what I claim as new, and desire to secure by Letters Patent, is—

1. In a coal-breaker, an open-bottomed barrel, a rotary breaker therein and a set of disintegrating-teeth carried by one of said parts

at the discharge end of the breaker, said set being one of a plurality of interchangeable sets, and the teeth of each set having a different length from the teeth of the other sets, whereby by using different sets of teeth the degree of fineness to which the coal is broken may be varied.

2. In a coal-breaker, an open-ended barrel, a rotary breaker therein, means to hold the barrel and breaker against relative movement in an axial direction, and a set of disintegrating-teeth removably carried by one of said parts at the discharge end of the breaker, said set being one of a plurality of interchangeable sets and the teeth of each set having a different length from those of the other sets, whereby by using different sets of teeth the degree of fineness to which the coal is broken may be varied.

3. In a coal-breaker, an open-bottomed barrel, a rotary breaker therein, and a set of disintegrating-teeth carried by the barrel opposite the lower end of the breaker, said set being one of a plurality of interchangeable sets, the teeth of each of said sets having a different length from those of the other sets, whereby by employing different sets of teeth the degree of fineness of the disintegration may be regulated.

4. In a coal-breaker, an open-bottomed barrel, a rotary breaker therein having a general conical shape, and a set of disintegrating-teeth projecting from the inner face of the barrel at its lower end and coöperating with the base of the breaker, said set being one of a plurality of interchangeable sets, and the teeth of each set having a different length from those of the other sets.

5. In a coal-breaker, an open-ended barrel, a rotary breaker therein, said barrel having at its discharge end an annular groove in its inner face and a set of disintegrating-teeth removably sustained in said groove, said set being one of a plurality of interchangeable sets, and the teeth of each set having a different length from those of the other sets, whereby by employing different sets of teeth the degree of fineness of the disintegration may be regulated.

6. In a coal-breaker, a barrel, a rotary breaker therein, an annular groove in the interior of the barrel, a plurality of separate disintegrating-teeth sustained in said groove, a keyway leading to said groove and through

which said teeth are inserted, and a key-tooth in said keyway.

7. In a coal-breaker, a sectional barrel open at both ends, a rotary breaker in said barrel, said barrel having an internal annular groove opposite the base of the breaker, a series of disintegrating-teeth removably supported in said groove, and a keyway extending through each section of the barrel and leading to the grooves, through which said teeth may be inserted.

8. In a coal-breaker, a sectional barrel open at both ends, a rotary breaker in said barrel, said barrel having an internal annular groove opposite the base of the breaker, a series of disintegrating-teeth removably supported in said groove, a keyway extending through each section of the barrel and leading to the grooves, through which said teeth may be inserted, one of said teeth being longer than the other and projecting into the keyway.

9. In a coal-breaker, an open-ended barrel, a rotary breaker therein, said barrel having an annular groove opposite the base of the breaker, a plurality of disintegrating-teeth removably supported in said groove, one of said teeth having an interlocking engagement with the barrel whereby said teeth are held against sidewise movement in the groove.

10. In a coal-breaker, a barrel having an annular wear-plate-receiving recess, wear-plates in said recess, an introduction-passage opening into the recess and through which the last wear-plate is inserted, and a closure-plate detachably secured in the introduction-passage.

11. In a coal-breaker, a barrel having an annular wear-plate-receiving recess in its inner face, and an introduction-passage opening into the recess, a plurality of wear-plates confined in said recess and forming the operative surface of the barrel, and a closure-plate detachably secured in the introduction-passage, the walls of the recess and the backs of the wear-plates having such a shape that when said plates are in mutual side contact they are prevented from moving sidewise in the groove.

12. In a coal-breaker, a barrel having a recess with polygonal walls, a plurality of wear-plates in said recess, each wear-plate having a flat back face to fit one of the flat sides of the recess, an introduction-passage opening into the recess and through which the last wear-plate is inserted, and a closure-plate detachably secured in the introduction-passage.

13. In a coal-breaker, a barrel comprising a base portion having vertical flanges, and a sectional hopper portion having ribs on each section thereof interlocking with the flanges on the base portion.

14. In a coal-breaker, a barrel comprising a base portion having a plurality of vertical holding-flanges, and a hopper portion having on its exterior a plurality of vertically-extending ribs to interlock with the flanges.

15. In a coal-breaker, a casing or shell hav-

ing an end discharge, a shaft in said shell, a breaker on the shaft, a gear-wheel also on the shaft and situated between the breaker and above the discharge-opening, and a stationary 5 circular shield between the breaker and gear to cover the gear, said shield being situated within the shell and of a size to leave an annular space between said shield and the walls of the shell through which the material is dis-10 charged.

16. In a coal-breaker, a casing or shell having an open discharge end and a spider extending across said end, a shaft journaled in said spider, a breaker on said shaft, a gear-

wheel on the shaft below the breaker and above 15 the spider, and a stationary circular shield covering the top of the gear and having depending flanges to inclose the sides of the gear, said flanges forming between them and the inner wall of the casing an annular space 20 through which the material is discharged.

In testimony whereof I have signed my name to this specification in the presence of two subscribing witnesses.

EDWIN S. DECKER.
